UNITED STATES PATENT OFFICE.

JULES ALBERT AGERON, OF PARIS, FRANCE.

ELECTRIC LIGHTING FOR VEHICLES.

SPECIFICATION forming part of Letters Patent No. 576,933, dated February 9, 1897.

Application filed August 2, 1895. Serial No. 558,000. (No model.) Patented in France May 18, 1895, No. 247,509.

To all whom it may concern:

Be it known that I, JULES ALBERT AGERON, of Paris, France, have invented new and Improved Electric-Light Devices for Lighting 5 Vehicles, Cars, Carriages, Velocipedes, and the Like, (for which I have obtained Letters Patent in France, No. 247,509, dated May 18, 1895,) of which the following is a full, clear, and exact description.

- 10 The object of my invention is to provide devices for the electrical lighting of wheeled vehicles, such as railway-carriages, automobile carriages and others, velocipedes, and the like.
- 15 The principle on which my invention is based is to derive the power for driving the electric machine from the vehicle itself and to conduct the current to lamps located at suitable places on the vehicle.
- 20 It is contemplated in my invention to provide means whereby the lighting will be effected not only during the forward travel of the vehicle, but also while the same is stationary or traveling backward. These objects
- 25 I attain by simple devices the dimensions and weight of which are such as not to interfere with the progress of the vehicle. I employ for the production of the electric current a continuous-current magneto-electric ma-
- 30 chine having its brushes so disposed as to permit of a rotation in either direction. In order to provide for the lighting of the vehicle during stoppages, an accumulator and an automatic circuit-breaker are interposed in the circuit. The accumulator supplies the required electric current when the magneto-electric machine is out of action, and at the same time the circuit-breaker interposed be-
- 35 tween said machine and the accumulator prevents a discharge from the accumulator into the circuit of the machine. Finally, in order to enable the lamps to remain lighted during the rearward travel of the vehicle I employ four automatic circuit-breakers each provided with two brushes. During the forward travel two of these circuit-breakers establish a communication between the poles of the machine and those of the accumulator, while the other two circuit-breakers are out
- 40 of contact and thus prevent the passage of the current into the circuit wherewith they are connected. During backward travel the

two first-named circuit-breakers are out of contact, while the two others establish communication between the poles of the machine 55 and those of the accumulator, so that the current which now flows through the machine in the opposite direction will always pass in the same direction through the accumulator. During stoppages the four circuit-breakers 60 will be out of contact, thus interrupting all communication between the accumulator and the machine as if there were only one circuit-breaker. The electric lamps which are provided at suitable places on the vehicle are 65 connected directly to the accumulator.

Reference is to be had to the accompanying drawings, forming a part of this specification, in which similar characters of reference indicate corresponding parts in all the views. 70

Figures 1, 2, and 3 are diagrammatic representations showing the application of my improved lighting system to a railway-carriage, an ordinary wheeled carriage, and a velocipede, respectively. Fig. 4 is a broken end 75 elevation, partly in section, of a railway-carriage with the improved electrical lighting devices attached thereto. Figs. 5 and 6 are a front view and a side view, respectively, of the improved lighting devices as attached to 80 an ordinary vehicle adapted for animal traction. Fig. 7 is a side elevation of a bicycle provided with my improvements. Fig. 8 is a detail sectional view of the magneto-electric machine and its connections. Fig. 9 is an 85 other sectional view thereof, taken at right angles to Fig. 8. Fig. 10 is a detail view of the means for throwing the electromagnetic machine into or out of action. Fig. 11 is an elevation, partly in section, of the improved 90 electromagnetic machine employed in connection with the velocipede. Fig. 12 is partly an end view and partly a cross-section on the line 1 2 of Fig. 11 of the said machine. Figs. 13 and 14 are a cross-section and a longitudi- 95 nal section, respectively, of the modified electromagnetic machine; and Figs. 15 and 16 are a longitudinal and a cross-section, respectively, of the automatic circuit-breaker em- 100 ployed in connection with my invention.

When the invention is applied to railway-carriages, it is necessary to so construct the lighting device that it will remain in action during movement of the car in either direc-

tion and during stoppage thereof. The device first shown in Fig. 1 therefore comprises the following main parts: the driving or transmission gear $s s' s^2$, the magneto-electric machine M, four automatic circuit-breakers D' D² D³ D⁴, an accumulator E, and electric lamps.

In the case of ordinary carriages adapted for animal traction it is not necessary to provide for lighting the vehicle during backward travel. The device in this case, therefore, comprises the following parts: the transmission-gear $t t' t''$, the continuous-current electromagneto-machine M, a single automatic circuit-breaker D, an accumulator E, and electric lamps.

In the case of velocipedes, Fig. 3, it is superfluous to have the lamp lighted in case of stoppage, and it will suffice to provide for the lamp being lighted during forward travel of the machine. The arrangement, therefore, may be considerably simplified, thereby reducing the weight of the attachment, a point which is of great importance in this class of vehicles. The device comprises only a transmitter-gear, as indicated at $u' u^2 u^3 u^4$, the electric machine M, and one lamp x.

As illustrated in Figs. 1 and 4, the improved lighting device when applied to a railway-carriage is arranged under the floor A of the said carriage in suitable hangers, as indicated at B, said hangers carrying bearings for the shaft c of the magneto-electric machine M. The shaft carries a sprocket-wheel r', engaged by a chain r² to another sprocket-wheel r on the axle of the car-wheel. D' D² D³ D⁴ are four automatic circuit-breakers of the class in which a body of mercury is used, said circuit-breakers being journaled in the frame or hangers B and in the cross-bar b, attached thereto. The brushes or contact-pieces for the said circuit-breakers are secured upon the frame B, but insulated therefrom. The shaft c of the machine carries two friction-disks d d⁰, which are constructed to screw upon the said shaft and are adapted for engagement with the friction-disks d' d² d³ d⁴ upon the circuit-breakers D' D² D³ D⁴. The friction-disks d and d⁰ are held between springs e e' e² e³, respectively, with force sufficient to prevent their rotation as long as the said friction-disks engage with the screw-threaded portions of the shaft c. Thus when the machine is started the said friction-disks will be held from turning on the shaft and thereby they will be obliged to travel longitudinally thereof until they come into frictional engagement with two of the friction-disks d' d² d³ d⁴. At the same time the friction-disks d and d⁰ have reached the end of the screw-threaded portions of the shaft c, and are thereby compelled to rotate with the shaft. If desired, stops may be provided on the shaft at the ends of the said screw-threaded portions, as indicated at e⁴ e⁵ e⁶ e⁷.

During the forward travel of the carriage the friction-disk d⁰ will be in engagement

with the disk d', and the friction-disk d will be in contact with the friction-disk d³, while during the rearward travel the positions of the said disks will be changed, as indicated in Fig. 4.

One of the brushes of the circuit-breaker D' is connected with the positive pole of the machine M and the other to the positive pole of the accumulator E, secured at any suitable place. The brushes of the circuit-breaker D³ are connected, respectively, to the negative pole of the machine and to the negative pole of the accumulator. One of the brushes of the circuit-breaker D² is connected to the negative pole of the machine and the other to the positive pole of the accumulator, and of the brushes of the circuit-breaker D⁴ one is connected to the positive pole of the machine and the other to the negative pole of the accumulator.

It will be understood that during forward travel only the circuit-breakers D' and D³ will be rotated. The mercury which is contained in each of them will establish a contact between the corresponding wires, as will be presently described, and the circuit is closed. During rearward travel only the circuit-breakers D² D⁴ will turn. The polarity of the machine is reversed, but it will be understood that the current is supplied to the accumulator E in the same direction as before. Figs. 1 and 4 indicate the circuits as they are during rearward travel.

When applying my improvements to the lighting of ordinary vehicles adapted for animal traction, it is sufficient to secure the machine indirectly upon the axle of the vehicle, (see Figs. 2, 5, and 6,) said axle being held against rotation. Between the axle and the surface upon which rests the magnets of the machine I interpose a disk or plate F, of diamagnetic material, such as copper. Motion is derived directly from the hub of the wheel by means of a toothed rim g, having internal engagement with the pinion g², the rim g being secured to a disk g', fixed upon the hub by means of screws and nuts and a conical recess, as shown. The pinion g² is mounted upon a shaft g³, supported in bearings g⁴ and g⁵, extending upwardly from the bracket G, which is secured upon the axle. The other end of the shaft g³ carries a toothed wheel g⁶, engaging with the pinion g⁷ upon the shaft c of the machine M. The accumulator E is arranged at any suitable point on the vehicle. A single circuit-breaker may be employed, as shown at D. The supports h h', between which the said circuit-breaker is held, are so arranged as to permit the circuit-breaker to rotate about its axis.

On the support h are secured the brushes of the circuit-breaker, one of which is connected to the positive pole of the machine and the other to the positive pole of the accumulator. Rotary motion is transmitted to the circuit-breaker D by means of bevel friction-disks h² h³, one of which is mounted

upon the machine-shaft c and the other upon the gearing of the circuit-breaker D.

When applying the invention to the lighting of velocipedes and bicycles, as shown in Figs. 3, 7, 8, 9, and 10, the construction of the electric machine is considerably simplified. In the drawings I have shown an alternating-current machine. As illustrated, the machine is supported on an aluminium bracket j , which is fixed to one of the members k of the rear fork of the frame. On the bracket j is carried a sleeve j' , in which is pivotally mounted the rod j^2 , terminated by a ring j^3 , in which is journaled the shaft l , carrying the friction-gear, whereby motion is transmitted to the machine. On one end of the said shaft l is secured a rubber disk or wheel l' , which engages the inner and side surface of the rim of the bicycle-wheel, and the other end of the said shaft carries a sprocket-wheel l^2 , from which motion is transmitted to the shaft c of the electric machine M by means of a chain l^3 and a sprocket l^4 on the said shaft c .

In order to prevent binding of the small wheels l' on the rim of the wheel and to keep these two parts in good contact, the rod j^2 is surrounded by a spring j^4 , which is coiled between two collars j^5 and j^6 , of which the latter is fixed to the rod j^2 . In order to throw the friction-wheels l' out of gear when it is desired to extinguish the light, the rider raises the handle m , which rests upon the wheel l' at one side and passes through apertures m' in the rod j^2 and the sleeve j' . As soon as the handle m comes out of the aperture or recess of the sleeve the rider may turn the rod j^2 , thereby removing the wheel l' from contact with the rim. In this construction no accumulator or circuit-breaker is required. The lamp x is placed in a reflector x' , which may have parabolic shape and may be provided with a lens, as shown.

The preferred construction of my continuous-current electric-light machine is shown in Figs. 11 and 12. This machine is distinguished by high efficiency with reduced volume and weight. The magnetic field is produced by six magnets n of the particular shape shown and connected in series of three by means of soft-iron pieces n' . The two series are placed opposite each other with similar poles adjacent to each other, but separated by means of the strip n^2 , of copper or other diamagnetic material. This construction allows of the utilization of almost the whole magnetic field.

The armature comprises the following parts: first, the iron core secured to the drive-shaft c ; second, the cores of the induced circuit; third, the commutator of the collector o ; fourth, the commutator-brushes $o' o^2$. The core is composed of a skeleton or drum p , whose outer surface is grooved longitudinally, so as to form ten recesses p' , separated by ribs p^2 and adapted to receive the armature-cores. The drum p is connected to the shaft c by means of arms or spokes p^3 , and the

space p^4 between the drum and the shaft c is filled with soft-iron filings. By this construction I reduce to a minimum the lost energy due to Foucault currents and to hysteresis. After the armature-wire is coiled on the drum p the cylinder thus formed is surrounded by an iron shell p^5 . This increases the permeability of the magnetic circuit. The wire is coiled in substantially the same manner as in the machine of the Siemens type, and the collector may be of the usual construction. The brushes $o' o^2$ are so arranged that they will allow the machine to turn in either direction, which is indispensable in the application of the invention to railway-carriages. For this purpose each brush comprises an elastic metallic rod o^3 , which is slideable upon a support o^4 , fixed to the frame of the machine through the medium of an insulating-piece o^5 . One of the ends of the rod o^3 is provided with a sleeve o^6 , adapted to receive the carbon block o^7 , which is tapering, so as to be of the shape of a truncated pyramid, and which is held in position by means of a clamping-screw. The elastic rod o^3 may hold the small end of the carbon block o^7 against the collector, and thus rotation may take place in either direction.

In the case of bicycles wherein small dimensions and small weight are indispensable I prefer to employ a slightly-modified construction. The machine employed in that case is an alternating-current machine and therefore has no collector. (See Figs. 13 and 14.) The conductors of the field-magnets are the same as in the continuous-current machine hereinbefore described. The armature is of much simpler construction, and consists of a single coil or spool. Finally, I have provided an improved arrangement whereby the brushes may be done away with, as clearly shown in the drawings.

The automatic circuit-breaker which I employ in connection with my invention consists (see Figs. 15 and 16) of a cylinder whose outer wall q is made of fibrous material at its center and of metal at two ends, as shown at $q' q^2$. The brushes $r' r^2$ of the circuit-breaker are in contact with the parts q' and q^2 . Within the ebonite cylinder q is placed a metallic cylinder made in two portions q^3 and q^4 , which are separated by an annular rim projecting from the inner side of the cylinder q . Each of the said hollow pieces or sleeves q^3 and q^4 is made integral with one of the ends q^2 and q' . The brush r , for instance, may be connected with the positive pole of the machine and the brush r' to the positive pole of the accumulator. The negative poles of the machine and of the accumulator are connected directly. In the circuit-breaker D there is a body of mercury reaching about to the level of the upper end of the sleeve q^3 . During the travel of the vehicle and the rotation of the circuit-breaker the mercury, in accordance with well-known physical laws, will assume the shape of a parabolic body at its upper surface, so that the marginal portions of the mercury

will rise sufficiently to establish communication between the sleeves q^3 and q^4 . As soon as the motion of the vehicle ceases the mercury will resume its horizontal level and thus 5 break the circuit.

Having thus described my invention, I claim as new and desire to secure by Letters Patent—

1. The herein-described automatic circuit-breaker consisting of a rotatable hollow body adapted to contain a conducting fluid and constructed of two sections of conducting material insulated from each other, substantially as set forth.
- 15 2. The herein-described automatic circuit-breaker, consisting of a hollow body mounted to rotate about a vertical axis and adapted to contain a conducting fluid, said body being constructed of two sections of conducting material separated by a horizontal ring of insulating material, substantially as set forth.
- 25 3. In a rotary circuit-breaker, a cylinder for containing mercury formed of two metallic end sections, and an insulating-sleeve receiving the end sections and provided with an annular rim projecting between the ends of the said end sections, as specified.
- 35 4. The combination, with a wheeled vehicle, of an electric generator operated by the rotation of the wheels, an accumulator electrically connected to the said generator, rotatable circuit-breakers in said connection, driving-disks movable from one circuit-breaker to the adjacent circuit-breaker, means controlled from the generator-shaft for rotating and longitudinally moving the said disks on their axes, and a lamp in circuit with the accumulator, substantially as described.
- 40 5. The combination, with a wheeled vehicle, of an electric generator operated by the rotation of the wheels, an accumulator electrically connected to the said generator, rotatable circuit-breakers in said connection, driving-disks screwing upon the generator-shaft and 45 movable from one circuit-breaker to the adjacent circuit-breaker, means for holding the said disks against rotation while they travel

longitudinally of the said shaft, and a lamp in circuit with the accumulator, substantially as described.

6. The combination, with a wheeled vehicle, of an electric generator operated by the rotation of the wheels, an accumulator electrically connected to the said generator, rotatable circuit-breakers in said connection, driving-disks screwing upon a shaft rotating with the generator-shaft, said disks being movable from one circuit-breaker to the adjacent circuit-breaker, springs clasping the said driving-disks between them to hold the disks 60 against rotation while they travel longitudinally of the said shaft, and a lamp in circuit with the accumulator, substantially as described.

7. The herein-described electric generator, comprising two series of field-magnets, each magnet having its poles facing each other, and the magnets of different series having their similar poles located adjacent to each other, magnetic bars connecting similar poles 70 of the magnets of one and the same series, diamagnetic strips separating the adjacent conducting-bars of different series, and an armature mounted to rotate between the poles of two field-magnets, substantially as set forth. 75

8. The combination with a velocipede, of an electric generator thereon, a rod fitted to slide and turn in a bearing on the machine-frame, a shaft mounted in one end of the rod, a friction-wheel on one end of the shaft, a 80 spring on the rod for holding the friction-wheel in engagement with one of the ground-wheels of the machine, gearing between the said shaft and generator, and a locking lever or handle for preventing the said rod from 85 turning in its bearing, substantially as described.

In witness whereof I have hereunto set my hand in presence of two witnesses.

JULES ALBERT AGERON.
